DESIGN FOR A COMBINATION POCKET CASE

Nicholas A. Mercer, New York, N. Y.

Application May 25, 1939, Serial No. 85,190

Term of patent 7 years

To all whom it may concern:

Be it known that I, Nicholas A. Mercer, a citizen of the United States, residing at New York, in the city and in the county of New York and State of New York, have invented a new, original, and ornamental Design for a Combination Pocket Case, of which the following is a specification, reference being had to the accompanying drawing, forming part thereof.

Figure 1 is a front elevational view of the combination pocket case in closed position showing my new design.

Figure 2 is a similar view in partly open position;

Figure 3 is a top plan view thereof in closed position; and

Figure 4 is a top plan view thereof in a completely open position.

I claim:

The ornamental design for a combination pocket case, as shown and described.

NICHOLAS A. MERCER.
